United States Patent Office

Des. 186,611
Patented Nov. 10, 1959

186,611

BEE AND FLOWER ACTION TOY

Willis M. Lakin, Chicago, Ill., assignor to Marlin Toy Products, Inc., Chicago, Ill., a corporation of Illinois

Application April 29, 1959, Serial No. 55,696

Term of patent 14 years

(Cl. D34—15)

FIG. 1

FIG. 3

FIG. 2

Fig. 1 is an elevational view of a bee and flower action toy embodying my new design;

Fig. 2 is a perspective thereof to reduced scale showing the same in extended condition;

Fig. 3 is a partial perspective view thereof in collapsed condition.

I claim:

The ornamental design for a bee and flower action toy, as shown.
